UNITED STATES PATENT OFFICE.

GEORGE L. MUHN, OF WHEELING, WEST VIRGINIA, ASSIGNOR OF ONE-HALF
TO JAMES H. McGEE, OF SAME PLACE.

GAGE FOR MORTISING-MACHINES.

SPECIFICATION forming part of Letters Patent No. 249,784, dated November 22, 1881.

Application filed September 10, 1881. (No model.)

To all whom it may concern:

Be it known that I, GEORGE L. MUHN, a resident of Wheeling, in the county of Ohio and State of West Virginia, have invented certain new and useful Improvements in Mortising-Machine Gages; and I do hereby declare that the following is a full, clear, and exact description of the invention, which will enable others skilled in the art to which it appertains to make and use the same, reference being had to the accompanying drawings, and to letters of reference marked thereon, which form a part of this specification.

The object of my invention is to provide a means to regulate the number and size of mortises to be made in the material without having to lay off the same on each separate piece of stuff, and also to insure accuracy in cutting up to the scribe, and avoiding liability of under or over cutting the mark, as is the case where the mortising is done by hand; and to this end my invention consists in the combination, with the table of a mortising-machine, of a sliding gage-bar, having adjustable studs on the upper edge, which, in connection with a stationary stop on the standard of machine, regulates the number and length of the mortises, and provided also with adjustable clamps or stop-blocks at each end, to secure the material and hold it in place while it is being mortised.

In the drawings, Figure 1 is a perspective view of a mortising-machine with my device attached to the table of the machine; Fig. 2, end view, showing relative position of the gage-bar and material with the mortising-chisel of the machine; Fig. 3, view of the mortise-stop on standard of machine; Figs. 4 and 5, enlarged side view and section of the gage-bar and track.

In the drawings like letters of reference refer to like parts.

The letter A designates a mortising-machine similar to those in general use, termed "a treadle-feed machine;" B, the table for supporting the material to be mortised; L, piece of wood to be mortised; C, the chisel; D, the treadle to raise the table.

E is a flat bar, of any desired length, suitable for the purpose it is to be used, having suitable size square grooves, *aa a*, plowed lengthwise in its sides.

F is a channel-bar, with the edges *b b* projecting inward and engaging with the grooves in the bar E, which slides through it. This channel-bar is attached to the table of the machine and moves up and down with it.

When it is required to mortise long stuff and to prevent the ends of the grooved gage-bar from sagging or bearing down from a level plane an extension-piece, *m*, is attached to each end of the channel-bar by means of a sliding-groove connection or other well-known ways, by which the track thus formed can be extended to any desired length.

G G are adjustable gages or stops secured to the upper edge of the slide-bars by a tongue-connection with a thumb-bolt to each to secure it in place. These pins are for the purpose of gaging the length of the mortise and operate in connection with a stop-pin, H, projecting from the standard of the machine on a horizontal line with the mortising-chisel and directly back of the same. The stop H is made adjustable vertically, to suit different widths of material, and is also made with a shoulder-joint to permit of it rising up when it is applied to certain kinds of machines where the gage-bar would have to pass it before the chisel would reach its required depth—such, for instance, as that class of machines known as "chisel-bar-feed machines," the device being applicable to both classes of mortising-machines. The stop-pin H and the mortise gage-pins G G are made preferably square or flat-sided where they engage with each other. The gage-pins G G can be increased in number according to the number of mortises to be made in the material, the length of the mortises being regulated by the distance of one pin from the other.

K K are stop-blocks, adjustably connected by a tongue-and-pin connection to the gage-bar, one at each end, for the purpose of clamping the ends of the material and holding it firm in connection with the gage-bar moving with the same. These stop-blocks permit of the material being reversed during the process of mortising to change the relative position of the mortises, if so desired; or the slide-bar can be withdrawn from its connection and reversed to change the position of the mortises. By the aid of this gage-bar the length and num-

ber of the mortises are determined, and the labor and inconvenience of laying off each piece of material separately are avoided, also having to redress the stuff to remove the scribe-marks.

5 Having described my invention, what I claim and desire to secure by Letters Patent of the United States, is—

1. In a mortising-machine, the combination of the table B, the track F, secured thereto, the grooved bar E, adapted to slide longitudinally, the independently-adjustable stops G on the slide-bar, and the stop-pin H.
- 10 2. The combination, in a mortising-machine,

of a movable gage-bar, E, having gage-pins G, and the adjustable stop-pin H, secured to the 15 standard of the machine and constructed with a loose joint to permit the pin to turn up out of the way of the gage-bar.

In testimony that I claim the foregoing as my own, I hereunto affix my signature, in presence of two witnesses.

GEORGE L. MUHN.
